CLAIM

The ornamental design for a combined safety flag and mounting bracket for a vehicle window, as shown and described.

DESCRIPTION

FIG. 1 is a perspective view of a combined safety flag and mounting bracket for a vehicle window showing my new design;

FIG. 2 is an enlarged view thereof; with the flag shown broken away for convenience of illustration;

FIG. 3 is an enlarged left side elevational view thereof; with the flag pole being removed;

FIG. 4 is a right side elevational view of the flag mounting bracket of FIG. 3;

FIG. 5 is a front elevational view of FIG. 3;

FIG. 6 is a rear elevational view of FIG. 3;

FIG. 7 is a top plan view of FIG. 3; and,

FIG. 8 is a bottom plan view of FIG. 3.

The portions of the flag that are not shown form no part of the claim.

The broken lines in FIGS. 1 and 2 represent a possible environment in which the design resides and form no part of the claimed design.
